UNITED STATES PATENT OFFICE.

WILLIAM A. VAN DEUSEN, OF CLEVELAND, OHIO.

FLUSHING APPARATUS.

Application filed November 29, 1927. Serial No. 236,436.

This invention relates to improvements in flushing apparatus of the class disclosed and claimed in Letters Patent No. 1,308,382, granted to me on July 1, 1919.

5 The objects of the present invention are to simplify, cheapen and improve the float sustaining and operating mechanism of my former flushing apparatus, and to provide a construction by which the manufacturing 10 costs are considerably lessened and the assembly of the parts greatly facilitated.

The foregoing objects, with other and more specific ones hereinafter appearing, are attained in the construction illustrated in the 15 accompanying drawings wherein Fig. 1 is a sectional front elevation of my improved flushing apparatus, showing the float and associated parts in the positions they occupy when the maximum water level prevails in 20 the tank; Fig. 2 is a plan view of the apparatus with the tank cover removed; Fig. 3 is an enlarged sectional detail, substantially on the line 3—3 of Fig. 1, showing the lower float sustaining link and parts associated 25 therewith; Fig. 4 is a view, similar to Fig. 1, showing the float in its lowest position as when the water has receded to its minimum level at which time it exerts no buoyant influence upon the float, the dotted lines in the 30 present view indicating the position to which the float is depressed and wherein it is temporarily held by the float depressing arm; and Figs. 5 and 6 are sections on the respective lines 5—5 and 6—6 of Fig. 1.

35 The tank, designated 1, is preferably made of vitreous china or porcelain, and is provided with a removable cover 2. A siphon, designated generally by the reference numeral 3, is desirably formed integral with 40 the tank, and it is shown as occupying the rear left hand corner, as the parts are viewed in Figs. 1, 2 and 4. The ascending leg 4 and descending leg 5 of the siphon are separated by a wall 6 (Fig. 6) the upper edge of 45 which constitutes what is commonly referred to as the "crown" of the siphon, the same being designated 7. The descending leg 5 connects at its lower end with a conduit 8 that leading along the rear wall to the transverse center of the tank and thence forwardly to the middle of the bottom wall and opens 50 through a boss that depends from the tank bottom and to which the flush pipe 9 is connected by means of a standard coupling provided for that purpose. The open bottom 55 of the ascending leg 4 is inclined, and its

higher edge is provided with a notch 10 forming what is known as the siphon "break." When the water level descends below said notch, the siphonic action is gradually broken.

A water supply pipe 11 is connected to the lower end of a pipe 12 which rises within the tank a suitable distance and has connected to its upper end, through a goose neck 13 and union 14, a valve 15 that has an outlet tube 16 directed toward the bottom of the tank. The valve is operated, through suitable connections involving lever mechanism 17, a rod 18, and relatively adjustable links 19 and 20, 70 from the float 21. The link 19 is adjustable through an aperture in a member 22 that is pivoted to the link 20, the link 19 being secured in any desired position with respect to said member by means of a set screw 23. 75

The float 21 is preferably drawn or pressed from a single sheet of copper or other suitable metal, and to the top wall of the float is riveted or otherwise secured a buffer plate 25 that is formed at one end with ears 26 to 80 which the link 20 is pivotally connected. A wear plate 27 is also preferably applied to the top wall of the tank to receive the thrust of the link 20 and thereby to protect the float against injury through frequent engagement 85 of the float with said link. The end of the buffer plate 25 opposite its connection with the link 20 is formed with a stop 28 for a purpose presently to be explained.

Secured to the inner side of the right hand 90 end wall of the tank, as the apparatus is viewed from the front, is a support 30 which is in the nature of a relatively narrow bar, and the connection between the tank wall and said support is desirably effected by means 95 of a cap screw 31 that is inserted from the outer side of the tank through a hole in said wall and is screwed into a tapped hole in the support. A layer 32 of suitable cushion material may be interposed between the support 100 and the tank wall. Extending from front to rear through the top of the support 30 is a pin 33, and extending rearwardly from the lower end of the support is a similar pin 34 (see Fig. 3). 105

The float 21 is open at its bottom, and disposed transversely of the float at its longitudinal center and in the same vertical plane are tubes 35 and 36 that are shown as located immediately below the top wall of the float 110 and immediately above the open bottom thereof, respectively. These tubes open

through the front and rear walls of the float, and the joint between said walls and the ends of the tube are suitably sealed. The vertical spacing of the tubes 35 and 36 is the same as that of the pins 33 and 34. Three links 40 are employed in my present preferred construction for connecting the float to the support 30, and these links are identical and interchangeable. Each link is constructed of a piece of tubing whose internal diameter is substantially the same as the diameter of the pins 33 and 34, and whose external diameter is substantially the same as the internal diameter of the tubes 35 and 36. As will be seen by reference to Fig. 3, where one of the links is shown in detail, the ends 41 are turned at right angles to the body portion of the link, and said body portion is flattened in a plane at right angles to the plane of said ends. Two of the links 40 have one of their ends engaged over the opposite ends of the pin 33 and their other ends inserted in the ends of the tube 35, while the respective ends of the remaining link are engaged over the pin 34 and within the rear end of the tube 36. Since all the links are of the same length, and in view of the fact that the spacing apart of the pins 33 and 34 is the same as that of the tubes 35 and 36, a "parallel rule" connection is effected between the float and the support 30 so that the float is maintained at all times with its open bottom horizontal.

A shaft 43 is extended through a bearing 44 in the front wall of the tank, above the float, and the rear end of the shaft is journaled in a bearing 45 supported by the rear wall of the tank in axial alignment with the bearing 44. The shaft 43 is held against forward displacement by means of a collar 44^a that is pinned to the shaft immediately inside of the bearing 44, and a weighted handle 46 is fastened to the laterally turned forward end of the shaft outside the tank. An arm 47 is secured to the shaft 43 centrally above the float and its free end is shown as equipped with a roller 48 that is arranged to engage the buffer plate 25 when the shaft is rotated in an appropriate direction by means of the handle 46.

In considering the operation of the apparatus, it will be assumed that water occupies the tank to the level indicated in Fig. 1 under which conditions the float 21 is maintained in its elevated position and through the connections previously described between the float and valve 15, the valve is held closed. When it is desired to flush the bowl, to which the tank is connected by means of the flush pipe 9, the handle 46 is turned in a direction to swing the arm 47 downwardly and engage the roller 48 thereof with the buffer plate 25 and depress the float to the position indicated by the dotted lines in Fig. 4 when the roller 48 will come to rest against the stop 28. This depression of the float displaces a sufficient

quantity of water through the siphon 3 to start the siphonic action and this action continues until the water level falls below the siphon break 10. As soon, however, as the water recedes to such an extent that the float is permitted to drop below the dotted line position shown in Fig. 4, pressure is released from the roller 48, and the arm 47 is permitted to return to normal position, under the counterbalancing weight of the handle 46 in which position it is shown in full lines in Figs. 1 and 4. Soon after the float starts to descend, the connections between it and the valve 15 are relaxed, allowing the lever mechanism 17 to assume a position in which the valve is open so as to admit water through the tube 16. After the siphonic action ceases, as above explained, the water begins to accumulate in the tank and it continues to do so until the float is again elevated to its highest position in which it closes the valve 15 through the connections hereinbefore described.

It will be seen from the foregoing description that my present invention provides a very simple, dependable and economical means for connecting the float to the tank and for depressing the float. In assembling the parts, the tank is first installed and connected to the flush and supply pipes 9 and 11 and the valve 15 is emplaced with its associated parts including the rod 18 and the link 19. The float 20, links 40 and support 30 are next assembled as described and are lowered into the tank and the screw 31 is engaged through the hole in the end wall of the tank and screwed into the support 30 so as to hold it and the float in place. It may here be explained that the links 40 are prevented from withdrawing from the pins 33 and 34 and from the tubes 35 and 36 by their proximity to the front and rear walls of the tank. No further means is necessary to hold the links in place. Prior to installing the float, the link 20 is connected to the ears 26 of the plate 25, wherefor it is only necessary after installation to make the connection between the link 20 and the link 19 which is done by engaging the upper end of the link 19 through the aperture in the member 22 and locking it therein by means of the set screw 23. Obviously this connection is made with the links 19 and 20 so adjusted with respect to each other that the valve 15 is held closed when the float occupies its maximum elevation. The shaft 43 is next inserted through the bearing 44, the collar 44^a and the arm 47 are then applied to the shaft and the shaft extended rearwardly to engage its end in the bearing 45, after which the collar 44^a and the arm 47 are suitably secured in place upon the shaft.

Having thus described my invention, what I claim is:—

1. In a flushing apparatus, the combination with a tank, of an open bottom float with-

- in the tank, parallel links pivotally connected at one of their ends directly to the float and at their other ends directly to supports fixed with respect to the tank for maintaining the float in position with its open bottom substantially horizontal at all times while permitting the float to rise and fall, a supply valve, operative connections between said valve and the float, means arranged to bear downwardly 50
- 10 on the float for depressing the same and maintaining it against rebound until the water falls below a predetermined level, and further means acting thereafter to restore the float depressing means to normal condition. 70
- 15 2. In a flushing apparatus, the combination with a tank, of an open bottom float within the tank, parallel links pivotally connected with a slip-joint connection at one of their ends to the float and likewise connected with a similar joint at their other ends to supports fixed with respect to the tank for maintaining the float in position with its open bottom substantially horizontal at all times while permitting the float to rise and fall, each link 75
- 20 being in close proximity to an adjacent wall of the tank and prevented thereby from becoming disconnected from the float and from the corresponding support, a supply valve, operative connections between said valve and the float, means for depressing the float and maintaining it against rebound until the water falls below a predetermined level, and further means acting thereafter to restore the float depressing means to normal condition. 80
- 25 3. In a flushing apparatus, the combination with a tank, of a support therein, an open bottom float within the tank, links of equal length pivotally connected at one of their 85
- 30 ends to spaced parts of the float and at their other ends to similarly spaced parts of the support whereby the tank is maintained in a position with its open bottom substantially horizontal at all times while being permitted to rise and fall, a supply valve, operative connections between said valve and the float, means for depressing the float and maintaining it against rebound until the water falls below a predetermined level, and further means tending to restore the float depressing means to normal position. 90
- 35 4. In flushing apparatus, the combination with a tank, of a support therein, pivot pins extending from the support, the float having bearing recesses, links having tubular bearing parts extending at right angles from their opposite ends, the bearing pins of the support and the bearing recesses of the float being spaced a like distance apart, respectively, 95
- 40 the bearing parts at the corresponding ends of said links being engaged within the bearing recesses of the float while those at the other ends of the links are journaled upon the pivot pins of the support, whereby the 100
- 45 float is maintained in position with its open 105
- 50 bottom substantially horizontal at all times while being permitted to rise and fall, a supply valve, operative connections between said valve and the float, means for depressing the float and maintaining it against rebound until the water falls below a predetermined level, and further means tending to restore the float depressing means to normal position. 110
- 55 5. In flushing apparatus, the combination with a tank, of a support secured to one of the end walls of the tank, said support having vertically spaced pivot pins, an open bottom float within the tank, said float having vertically spaced bearing recesses that are spaced apart a like distance to the spacing of said 115
- 60 pivotal pins, links of equal length formed of tubing having their ends turned at right angles to their body portions, and having one of their ends journaled on the pivot pins of the support and their opposite ends contained within the bearing recesses of the float whereby the float is maintained in position with its open bottom substantially horizontal at all 120
- 65 times while being permitted to rise and fall, a supply valve, operative connections between said valve and the float, means for depressing the float and maintaining it against rebound until the water falls below a predetermined level, and further means tending to restore the float depressing means to normal position. 125
- 70 6. In flushing apparatus, the combination with a tank, of a support located within the tank adjacent an end wall thereof, a device for securing said support to said end wall, bearing pins extending laterally in both directions from the top of the support, a bearing pin extending laterally from the bottom of the support in substantially parallel relation to the beforementioned bearing pins, tubes carried by and extending transversely of the float and spaced apart in a vertical plane a like distance to the spacing apart of the upper and lower bearing pins of the support, links of equal length and corresponding in number to the bearing pins of the support, said links being formed of tubing and having their ends turned at right angles to their body portions and their body portions flattened in a plane at right angles to the plane of said 130
- 75 ends, one of the ends of said links being engaged over the bearing pins of the support and the opposite ends journaled in the corresponding tubes of the float whereby the float is maintained in position with its open bottom substantially horizontal at all times while being permitted to rise and fall, a supply valve, operative connections between said valve and the float, means for depressing the float and maintaining it against rebound until the water falls below a predetermined level, and further means tending to restore the float depressing means to normal condition. 135
- 80 7. In flushing apparatus, the combination 139

- with a tank, of a support within the tank, bearing pins extending laterally from the support, tubes carried by the float in parallel relation to said pins and spaced apart a like distance to the spacing apart of the pins, links of equal length and corresponding in number to the bearing pins of the support, said links having tubular ends disposed at right angles to their body portions, one of the ends 10 of said links being engaged over the bearing pins of the support and the opposite ends thereof journaled in the ends of the corresponding tubes of the float whereby the float is maintained in position with its open bottom substantially horizontal at all times while being permitted to rise and fall, a supply valve, operative connections between said valve and the float, means for depressing the float and maintaining it 20 against rebound until the water falls below a predetermined level, and further means tending to restore the float depressing means to normal condition, the space between the float and the walls of the tank wherein said 25 links are disposed being considerably less in width than the length of the tubular ends of the links whereby said ends are prevented from withdrawing from the bearing pins and tubes.
- 30 8. In flushing apparatus, the combination with a tank, of a float within the tank, a supply valve, operative connections between said valve and float, a shaft pivotally supported by the tank above said float, an arm on said 35 shaft that is normally out of contact with, but is adapted to engage and depress, the float when the shaft is rocked, and a handle for rocking the shaft, the arm serving to maintain the float depressed against the buoyancy 40 of the water until the water falls below a given level, and the handle acting thereafter by reason of its weight to swing the shaft in a direction to restore the arm to its normal position.
- 45 9. In flushing apparatus, the combination with a tank, of an open bottom float in the tank, means constantly maintaining the float in position with its bottom substantially horizontal while permitting the float to rise and 50 fall, a supply valve, operative connections between said valve and the float, an arm pivotally supported above and normally out of

contact with the float and arranged when swung on its pivot to engage and depress the float and hold it depressed against the buoyancy of the water until the water falls below a predetermined level, a stop on the float that limits the swing of the arm, and means acting after the water falls below said level to return the arm to normal position. 60

10. In flushing apparatus, the combination with a tank, of an open bottom float in the tank, means constantly maintaining the float in position with its bottom substantially horizontal while permitting the float to rise and fall, a buffer plate secured to the top of the float, a supply valve, operative connections between said valve and one end of said plate, the opposite end of the plate being formed to provide a stop, an arm pivotally supported 70 above the float and arranged when swung on its pivot to engage said buffer plate and depress the float, the arm engaging said stop and serving to maintain the float depressed against the buoyancy of the water until the water falls below a predetermined level, and means acting thereafter to return the arm to normal position. 75

11. In a flushing apparatus, the combination with a tank, of an open bottom float within the tank, means constantly maintaining the float in position with its bottom substantially horizontal while permitting the float to rise and fall, a buffer plate secured to the top of the float and having one of its ends formed for pivotal connection with a link and its opposite end shaped to provide a stop, a link pivotally connected to the first mentioned end of the buffer plate, a supply valve, operative connections between said valve and said link, an arm pivotally supported above the float and arranged when swung on its pivot to engage the buffer plate and depress the float, said arm being limited in its swinging movement by contact with the aforesaid stop and serving to maintain the float depressed against the buoyancy of the water until the water falls below a predetermined level, and means acting thereafter to return the arm to normal position. 95

In testimony whereof, I hereunto affix my signature.

WILLIAM A. VAN DEUSEN.
